US00D770134S

(12) **United States Design Patent** (10) **Patent No.:** **US D770,134 S**
Luevano, III (45) **Date of Patent:** **** Nov. 1, 2016**

(54) **UNIFORM INCLUDING SAFETY HANDLES**
(71) Applicant: **Agapito Luevano, III**, Burleson, TX
(US)
(72) Inventor: **Agapito Luevano, III**, Burleson, TX
(US)
(**) Term: **14 Years**
(21) Appl. No.: **29/516,161**
(22) Filed: **Jan. 29, 2015**
(51) **LOC (10) Cl.** **02-02**
